CLAIM

The ornamental design for a cat scratching sofa guard, as shown and described.

DESCRIPTION

FIG. 1 is a front elevation view of a cat scratching sofa guard.

FIG. 2 is a back elevation view of the cat scratching sofa guard.

FIG. 3 is a right elevation view of the cat scratching sofa guard.

FIG. 4 is a left elevation view of the cat scratching sofa guard.

FIG. 5 is a top elevation view of the cat scratching sofa guard

FIG. 6 is a bottom elevation view of the cat scratching sofa guard.

FIG. 7 is a perspective view of the cat scratching sofa guard, when applied on a sofa; and,

FIG. 8 is a second perspective view of the cat scratching sofa guard, when applied on the sofa.

(Continued)

The broken lines in the drawings illustrate portions of the cat scratching sofa guard which form no part of the claimed design.

1 Claim, 8 Drawing Sheets
